PERCOLATOR TOP

Emiel P. Seghers, Chicago, Ill.

Application December 8, 1930, Serial No. 500,712

44 Claims. (Cl. 53—3)

My present invention relates to percolator covers comprising a lid and top, and particularly to the means for holding the percolator top within the opening in the lid of a coffee percolator or the like. One object of this invention is to hold the percolator top resiliently within the opening so that said top and lid may be free to expand and contract relatively to each other without permitting the top to become loose in said opening.

Another object of this invention is to prevent rotation of the top within the opening in the lid. The reason for doing this is so that the top will not rotate into such a position that the same may be removed from the lid as ordinarily percolator tops must be separable from the lid in some manner in order that the same may be replaced when desired. Percolator tops are made of glass and crack quite readily, thereby necessitating replacement at frequent intervals.

Another object of this invention is to provide a percolator top adapted to be used with an improved form of percolator lid to get improved results, but which at the same time is capable of being used with percolator lids now on the market without necessitating any changes in the lid.

More specifically my invention contemplates using resilient means for holding the percolator top within the opening in the lid, the resilient means also preventing rotation of the top within the lid.

My invention is equally applicable to percolator lids provided with a depending flange surrounding the opening therein, or with lids having no depending flange. The former style of percolator lid is commonly used on aluminum percolators, whereas the latter form is used particularly on enameled percolators.

Other objects of this invention will appear hereinafter as the description thereof proceeds, the novel combinations and arrangement of the various parts being clearly set forth in the appended claims.

In the drawings—

Fig. 1 represents a bottom plan view of a percolator top showing the top and lid in operative relation with each other;

Fig. 2 is a section taken substantially along the line 2—2 of Fig. 1;

Fig. 3 is a bottom plan view of a modification of my invention employing an insertable ring adapted to be used particularly on enameled percolators;

Fig. 4 is a section taken along the line 4—4 of Fig. 3;

Fig. 5 is a fragmentary perspective view of a portion of the top showing my improved form of lug and the end portion of the spring which is adapted to co-operate therewith;

Fig. 6 is an enlarged elevational view of a portion of the depending flange or apron on the top showing the improved form of lugs used thereon;

Fig. 7 is a perspective view of the spring clip shown in Figs. 1 and 2;

Fig. 8 shows a section through a lid of ordinary construction with a top according to my invention and a retaining ring adapted to hold the top and lid in proper relation to each other;

Fig. 9 is a section taken substantially along the line 9—9 of Fig. 8 showing the bayonet slot in the flange on the lid and a corresponding depression in the retaining ring;

Fig. 10 is an elevational view of a still further modification of my invention, parts being broken away to better illustrate this form of the invention;

Fig. 11 is a section taken along the line 11—11 of Fig. 10;

Fig. 12 is a section taken along the line 12—12 of Fig. 10;

Fig. 13 is a view showing a modified form of the lug shown in Figs. 10 and 12;

Fig. 14 shows a still further modification of the lug shown in Figs. 10 and 12;

Fig. 15 is a section taken along the line 15—15 of Fig. 14;

Fig. 16 is a bottom plan view of Fig. 14;

Fig. 17 is a bottom plan view of a still further modification of my invention;

Fig. 18 is a section taken along the line 18—18 of Fig. 17;

Fig. 19 shows a modified form of the invention shown in Fig. 18; and

Fig. 20 shows still another modification of my invention.

The ordinary aluminum percolator lid is constructed substantially as shown in Figs. 1 and 2. The main portion of the cover is indicated by the reference numeral 1. The cover is provided with a central opening surrounded by a depending flange 2. This flange may be vertical and in some cases is vertical. More often however, the flange slopes downwardly and inwardly as clearly illustrated in Fig. 2. The top 3 is usually provided with a bead or limiting abutment 4 which surrounds the top and is adapted to rest against the upper surface of the lid adjacent the opening in

the latter. The top also has a depending cylindrical apron or flange 5 of substantially cylindrical shape which is ordinarily provided with two projections 6 of substantially semi-spherical shape 5 located at opposite sides of the flange.

The construction so far described is the common construction found in most aluminum percolators now on the market. Means however, must be provided for holding the top in the opening of the lid and yet permit removal of said top from said opening when desired. The ordinary provision made for accomplishing these results, is to provide projection receiving depressions or recesses 7 in the depending flange 2. These recesses 7 are ordinarily referred to as bayonet slots. The top is inserted in the lid by arranging the projections 6 in alignment with recesses 7 and moving the top downwardly into the opening, the recesses permitting the projections 6 to move into 20 a position below the lower edge of the flange 2. Then by rotating the top through substantially 90° the projections 6 are brought into position beneath portions of the flange 2, which are not provided with the recesses 7. Therefore, upward 25 movement of the top is prevented by the engagement of the projections with the under edge of the flange. In forming the recesses 7 the ordinary method is to form the flange 2 with the recesses 7 therein, but when inserting the top 3 into the 30 opening in the lid the pre-formed recesses are disregarded and the tops are forced into the opening by machines so that the projections 6 will themselves form the recesses 7 if the pre-formed recesses and projections do not coincide. It is 35 possible to do this in view of the fact that the lid of the percolator is generally made of relatively thin material which is quite pliable and yields under pressure.

The disadvantages of such a construction are 40 quite numerous and a great many ways have been suggested for overcoming the difficulties which are encountered with the aforesaid construction. Some of the disadvantages are as follows:

In the first place the top and lid are of different materials, namely, glass and metal respectively, and the result is that there is an unequal expansion of these materials, and the expansion of each of these parts occurs generally at different times. As is well known, the coffee is forced 45 against the top part of the inner side of the percolator top and is deflected by the percolator top back onto the coffee which is in a basket arranged in the top of the percolator. Therefore the top is directly engaged by coffee which is at 50 boiling temperature and the top expands quite rapidly and before the lid has been heated to any appreciable extent. Therefore the cylindrical apron or flange portion 5 of the top tends to enlarge the opening in the lid by forcing the 55 lower edge of the flange outwardly, and as the flange is quite pliable, there is a permanent distortion imparted to the flange. The flange could not be made strong enough to withstand this distortion as it would be apt to crack the glass top, 60 which of course would be quite undesirable. When the parts cool down, the top contracts and so does the lid, but since the opening has been made larger by the expansion of the top, the top will no longer fit snugly within the opening even 65 though the same may have fit snugly in the opening when first placed therein.

If the top is loose within the opening, the top will rotate freely and without being apparent to the user of the coffee percolator, the projections 6 70 will position themselves in time, adjacent the

recesses 7 and when the cover is raised to open position, the top will quite likely fall out of the lid and if it strikes a solid object, will no doubt break as the glass from which these tops are made is quite brittle in view of the fact that they are generally made by die casting. Sometimes the top deforms the flange 2 to such an extent 5 that the projections 6 may pass the flange without being arranged adjacent the recesses 7. The projections 6 are not ordinarily of more than $\frac{1}{16}$ " 10 in height and a great many times are not that high. If the knob 8 on the top is grasped when, opening the cover and the top does not fit within the opening in the lid quite snugly, the projections 15 may pass the flange 2 without much trouble. 15

Another difficulty with the deformable flange 2 is that the user is quite apt to use the top in the improper manner. For instance in a great many lids the depressions 7 are not very noticeable and a person will push the top down into the 20 opening in the lid without first locating the projections in the proper position. The result is that additional recesses, such as 7 are formed about the periphery of the flange 2. If this is done very often, the result is that there is not much of the 25 flange which will prevent the projections from passing out of the opening after the top has been inserted therein.

It is quite obvious that in addition to the aforesaid disadvantages, there is the disadvantage of 30 having a loose top arranged within the opening in the lid thereby causing considerable rattling. Also it has been found that the distance between the projections 6 and the bead 4 varies considerably, and vertical movement of the top in the 35 opening ordinarily will result.

Other disadvantages of the ordinary construction will appear as the description of this invention proceeds.

I will first describe the preferred form of my 40 invention which is shown in Figs. 1, 2, 5, 6 and 7. In this form of the invention, in addition to the projections 6, I provide the wedge-shaped projections 9 on the depending flange or apron 5 of the top 3, with the faces of the wedge-shaped 45 lugs opposed to the bead 2. This projection 9, as best illustrated in Figs. 5 and 6, is substantially a one-half section of a right circular cone. The apex of the conical projection 9 extends upwardly, and terminates approximately near the underside 50 of the projection 6 as in Fig. 6. It is not necessary that the projection 6 and projection 9 be arranged in axial alignment with each other, but may be spaced peripherally with respect to each other. Furthermore the projection 9 may be used 55 by itself although it is preferred to also use the projection 6. In constructing the top, it may even be found desirable to make the projections 6 and 9 so that they merge one into the other with a depressed portion between them as in Figs. 60 2, 3 and 18.

I wish to have it understood to begin with that in constructing my invention, I have borne in mind the fact that in order to replace percolator tops which are now on the market, it is necessary 65 that my percolator top be so constructed, at least for a considerable time, so that the same may be used with the usual type of percolator lid, as well as with spaced raised portions such as my new and improved type of percolator lid, 70 which is provided with a spring as will appear hereinafter. It will readily be seen therefore that a top with the projection 6 thereon, as well as the projection 9, may be used with the ordinary lid as the ordinary top is also provided 75

with a projection such as the projection 6. The projection 6 in my invention has a function corresponding to the ordinary function of a projection positioned in this place on a percolator top. That is, it is located near the depending flange 2 and prevents the removal of the top vertically out of the opening when the projections have been rotated out of registration with the recesses 7.

10 It has also been borne in mind in making my invention that my improved form of percolator lid must be capable of using the ordinary type of percolator top in emergency. Therefore, with these objects in mind I have provided an improved percolator cover which has a lid capable of using the ordinary style of percolator top and have also provided a percolator top which may be used with the ordinary style of percolator lid.

20 To the underside of the cover 1, at diametrically opposed points thereon, I fasten the springs or resilient fingers 10 by means of the rivets 11. These springs have a cross-section substantially as shown in Fig. 2. It will be noted that this cross-section is such that there is a portion 11' intermediate the free end of the spring, and that end which is against the cover, which will permit the passage of the projections 6 thereunder so as not to interfere with the rotation of the top 3. It is not very practicable to provide springs which will engage the projections 6 so as to prevent rotation of the top within the opening in view of the fact that the projections 6 are arranged in close proximity to the flange 2 and the result would be that one could not obtain very much of a spring action because the spring would abut against the flange and when deformation of the flange occurred by expansion of the top 3, then the usefulness of the spring would be practically destroyed. Accordingly I provide a rather long spring having a notch 12 formed in the outer free end thereof and this notch is adapted to receive the projection 9 so that the portions of the spring on opposite sides of the notch 12 will rest against opposite sides of the projection and prevent rotation.

25 Due to the length of the spring, there is not as much angular flexing of the spring as is necessary with a shorter spring and therefore by having the spring engage a projection remote from the cover, there is less tendency for the spring to break down due to the fatigue of the metal. Furthermore if for any reason the springs are deformed permanently in a direction outwardly from the top, a person may readily re-position the springs in their former shape by engaging the outer sides of the springs with a blunt instrument or with the fingers and exerting a pressure towards the axis of the opening. This is not possible with short springs in view of the fact that substantially all of the effective portion of a short spring made to engage projections such as the projections 6 must respectfully abut against the flange 2. Furthermore, with a short spring there is more angular bending, and fatigue of the metal occurs more quickly.

30 Due to the conical surface on the projection 9 it is quite immaterial whether there is a difference in the spacing of the projection 9 on various tops. It is quite to be expected that the projections 9 will not all be at the same distance from the bead 4. Due to the resilient action of the spring however, if the projection is close to the bead 4, the spring will ride on the projection 9 near the bottom thereof, whereas if the projec-

tion is farther away from the bead 4, the spring will ride against the upper portion of the projection 9.

35 If there is an expansion in a vertical direction of the top 3, then of course, the ends of the springs will ride over the surfaces of the projections 9 and while holding the top firmly within the opening, it will be found that the expansion of the top and lid relatively to each other is not interfered with.

40 If the opening in the lid becomes large, due to the expansion of the top 3, or if there is a difference between the size of the opening and the outer periphery of the flange 5, the springs will prevent lateral movement of the top within the opening as effectively as they would if the flange and opening fit snugly with respect to each other.

45 Due to the die casting of the top, there remains a small flange or fin 13, which is left at the lower edge of the projection 9 as illustrated in the enlarged view shown in Fig. 6. This fin acts as a stop shoulder against which the end of the spring abuts in the event that the projection 6 is permitted to pass the flange 2, or in the event that there is no projection such as the projection 6.

50 With this arrangement it is assured that the top cannot be removed from the lid without moving the ends of the spring over the fin 13.

55 It must be borne in mind that the flange or apron 5 can only be made of a limited depth in view of the fact that the basket which holds the coffee has the top portion thereof in substantially the same plane as the lower edge of the top when the cover is closed. By placing the projection 9 at the lowermost portion of the flange 5, a maximum utilization is made of the space between the lid and the top of the basket.

60 Due to the length of the springs, a small amount of lateral deflection thereof is permitted so that if the projections 9 are not diametrically opposed, then the springs may yield slightly to one side or the other so that the projections will be properly received within the notches 12.

65 It is not necessary to use two projections and two springs as it has been found that a single projection and a single spring will suffice to hold the top in the opening. It is preferred however, to have the two projections and the two springs and more if desired. If the diameter of the flange 5 is smaller than contemplated, the ordinary resilient action of the springs will permit for compensation of this difference, whereas with the short spring such a compensation is impossible.

70 It will be noted from an inspection of Figs. 1, 2, 6 and 7, that the outer free end of the spring is provided with angularly bent portions 14 which form wings or cam surfaces which permit the spring to ride up over the projection 9 when the percolator top is rotated to position the projection 9 in proper relation with the spring 10.

75 Instead of arranging the projections 6 and 9 in alignment with each other, the same may be spaced 90° from each other in a peripheral direction as in Fig. 20, or at any other desired angle. With such a construction however, it is necessary to provide four recesses such as the recesses 7. The additional recesses may be formed merely by forcing the top against the flange 2, the same as when the cover is being made.

80 In Figs. 3 and 4, I have shown a modified form of my invention which is particularly adapted to porcelain or enameled percolator lids. In this construction I provide a ring 15 having the bayonet slot 16 and depending spring fingers 17. The ring portion 15 has a circumferential recess 75

which receives the edge 18 of the porcelain cover 19. Porcelain and enameled covers ordinarily do not have a depending flange. The ring 15 may be snapped into place in the ordinary percolator 5 cover for this type of percolator, then the springs expand and the bayonet recess 16 enters the bayonet recess in the cover thereby preventing rotation of the ring. The springs 17 are notched as at 19' the same as are the springs 10 and 10 operate with the projections 9 in the same manner as in Figs. 1 and 2.

In Figs. 8 and 9, I have shown a construction which enables me to adapt my invention to the ordinary percolator lid so as to secure the benefits of my invention without changing the construction of the ordinary percolator lid. In this form of the invention, the cover 1 is constructed the same as in Figs. 1 and 2, and the top 3 is also constructed the same as in Figs. 1 and 2. 20 A ring 20 formed by rolling a piece of metal about itself has a bayonet slot 21 therein, similar to the bayonet slot 16 of ring 15 in Fig. 4 so that when the ring is placed beneath or around the flange 2, the ring is prevented from rotating 25 with respect to the flange while at the same time not interfering with the passage of the projections 6 into the opening. The ring need not be continuous but may be formed as a split ring, the opposed ends being later secured together or 30 not as may be desired. At diametrically spaced points about the ring 20, I provide the spring fingers 21 which act in a manner and are constructed similar to the spring fingers 10 and 17 in Figs. 1, 2, 3 and 4.

Figs. 10, 11 and 12 illustrate a form of my invention shown in Figs. 13, 14, 15 and 16 of my application Serial No. 292,278 filed July 12, 1928. The only substantial difference between the form of the invention shown in Figs. 10, 11 and 12 of 40 this application, and Figs. 13, 14, 15 and 16 of Serial No. 292,278 is in the form of the spring which is used, the spring being shaped so as to co-operate with the projection, such as the projection 9, as well as the projection shown in Figs. 45 10, 11 and 12.

In this form of the invention, the top 22 is provided with a depending flange or apron 23 formed with diametrically opposed projections thereon. Each projection has a depression or recess, the 50 vertical side portions 24 substantially V-shaped in cross-section as best illustrated in Fig. 12, and a bottom portion 25 which is beveled as best illustrated in Fig. 11. The spring 26 formed in a manner similar to the spring 10, has the end 55 thereof engaging the lower beveled surface 25, and the edges of the spring engage the vertical portions 24, so as to prevent rotation of the percolator top within the opening. Withdrawal of the top from the opening is prevented by the 60 upper ends of the vertical portions 24 which terminate just below the lower edge of the flange 2 and serve the same purpose as do the projections 6 although they accomplish their result in a 65 more effective manner due to the horizontal upper surfaces thereon. The operation of this device is quite obvious.

The top shown in Fig. 13 has a projection thereon formed similar to the projection shown in Fig. 12, but the depression 27 in the projection 70 is substantially spherical instead of being flat at the bottom and tapered at the sides as in Fig. 12. The walls of the depression 27, namely, the walls 24' and 25' correspond to the walls 24 and 25 in Figs. 10, 11 and 12, and perform the same function.

Figs. 14 and 15 show a still further modification of the projection shown in Figs. 10, 11 and 12. In this modification, the vertically extending portions 24'' of the depressions or recesses are notched as at 28 so that it will not be necessary for the spring to be flexed as much as with the device shown in Fig. 10, thereby lengthening the useful service of the spring. However, the springs ride over the projections 24'' the same as in Figs. 10, 11 and 12, so that when the spring is arranged 10 between the projections 24'', rotation of the top will be prevented except when a considerable force is applied thereto.

When using tops such as shown in Figs. 10, 11, 12, 13, 14 and 15 it is necessary to use a bayonet 15 slot 7' which is wide enough to enable the projection to pass through the rim portion 2.

A still further modification of my invention is shown in Figs. 17 and 18 in which a separate ring is used for the purpose of adapting a top constructed according to my invention to a lid of the ordinary construction. The arrangement is somewhat the same as shown in Fig. 8, except in this instance the ring 29 is substantially L-shaped in cross-section, and is practically a solid ring 25 and does not have the spring fingers 21 shown in Fig. 8. The upper portion of the ring has a flat annular portion 30 which abuts against the lower side of the cover 1. The ring is provided with an upwardly and inwardly extending flat annular 30 flange 31 which is notched at 32 so that the ring may be slipped over the top from beneath, notches 32 being for the purpose of receiving the projections 6 and 9. The ring is inserted from beneath and is then rotated. The flange 31 is slit 35 peripherally at 33 for a short distance so as to form spring tongues 34. The flange 31 and ring 29 are resilient and therefore when the flange 30 abuts against the underside of the lid 1, the flange 31 will be forced against the upper 40 sloping surfaces of the projections 9 to prevent separation of the top and cover in substantially the same manner as the ring 20 and spring fingers 21 prevent this separation in Figs. 8, 9 and 10.

In Fig. 19, I show an arrangement such as in 45 Figs. 17 and 18 but with the flange 30, recesses 32 and slits 33 omitted. Since there is no flange on the ring 29, the ring may be forced out of round by pressing the opposite sides toward each other. The dimension of the ring in one direction is 50 thereby increased to such an extent as to permit the ring to be slipped over the flange 5 and projections 6 and 9 with ease. When the ring again contracts the flange 31 resumes its circular shape 55 and grips the upper sloping surfaces of projections 9 therebetween.

The edge of the flange 31 is serrated as at 35 so that the serrations will position themselves over the projections 9 and prevent rotation of the ring relative to the projections. While with this 60 modification, it is not absolutely necessary that the ring be prevented from rotation relatively to the lid 1, I may if I so desire, provide the upper edge of the ring with a bayonet slot to fit over the bayonet slot ordinarily provided on the cover 65 and in a manner similar to that illustrated in Figs. 3 and 4 and also 8, 9 and 10.

While I have shown a number of modified arrangements for my invention, it will readily be seen that all of these forms embody substantially 70 the same basic principle, namely, the provision of a projection which has a downwardly and outwardly sloping surface, a lid which has a relatively long spring for engaging the sloping surface at a point remote from the flange on the lid and 75

additional sloping surfaces for engaging portions of the spring to prevent relative rotation between the top and the lid.

Obviously other changes may be made in the construction and in the arrangement of parts without departing from the spirit of this invention, and I do not wish to be limited except as set forth in the appended claims.

Having thus described several modifications of my invention, what I desire to secure by Letters Patent of the United States is:

1. In a percolator cover, the combination with a lid having an opening therein, of a glass top for said lid having a portion adapted to be arranged within said opening, a projection on said top for engaging the edge of said opening to resist withdrawal of said top from said lid, a second projection on said top spaced from said first projection in a direction away from the edge of said opening, and a spring co-operating with said lid and said top and resiliently engaging said second projection to hold said top firmly within said opening and thereby prevent rattling thereof while permitting unequal expansion and contraction of said top and lid.

2. In a percolator cover, the combination with a lid having an opening therein, of a glass top for said lid having a portion adapted to be arranged within said opening, a projection on said top for engaging the edge of said opening to resist withdrawal of said top from said opening in said lid, a second projection on said top spaced from said first projection in a direction away from the edge of said opening, and a spring co-operating with said lid and top for resiliently engaging said second projection to hold said top firmly within said opening to prevent rattling thereof while permitting unequal expansion and contraction of said top and lid, said spring also having means thereon co-operating with means on said top for resisting rotating of said top in said lid.

3. In a percolator cover, the combination with a lid having an opening therein, of a glass top having an apron extending into said opening, means on said top for limiting movement of said top into said opening by engagement with said lid adjacent said opening, an abutment surface on said apron having the operative surface thereof spaced a substantial amount from the edge of said opening and in a direction away from a plane through the edge thereof, and a yielding member arranged between said abutment surface and said lid and co-operating with said top and lid for preventing withdrawal of said top from said lid, but permitting relative expansion of said top and lid, said yielding means and abutment surface having co-operating means thereon to resist relative rotation between said top and lid while said top is arranged within said opening.

4. A percolator cover comprising a lid having an opening therein, a flange depending from said lid and surrounding said opening, a glass top having a portion thereof extending into said opening and projecting beyond said flange at both sides thereof, means on said top for engaging means on one side of said lid for limiting movement of said flange into said opening, a projection on said top for engaging the edge of said flange on the other side of said lid to prevent withdrawal of said top from said opening while said top and lid are in one position of rotative adjustment, said flange having a recessed portion therein arranged in the direction of the axis of said opening for permitting said projection to pass through

said opening, a second projection arranged on said percolator top and spaced from said flange in a direction below the plane through the lower operative edge of said flange when said top is within said opening, and spring means on said lid having yielding engagement with said second projection and being shaped to clear said first projection when said top is rotated within said opening.

5. In a percolator cover, the combination with a lid having an opening therein, of a glass top having an apron thereon projecting through said opening to position one portion of said apron below said lid, a projection on said apron spaced a substantial amount from the edge of said opening, a ring surrounding said apron between said projection and said lid, a spring finger on said ring for engaging said projection, said ring abutting against said lid to urge said spring finger into engagement with said projection, said projection being constructed to engage said spring finger to permit relative expansion of said top and lid without destroying the operative contact of said spring finger with said projection, and said spring finger preventing rattling of said top in said opening due to its yielding engagement with said projection, and a second projection on said top for engaging the lid to resist removal of said top from said opening.

6. A percolator cover comprising a lid having an opening therein, a ring fitting within said opening and having portions engaging the edge of said opening and overlying the adjacent surfaces of said lid to retain said ring in said opening, spring fingers on said ring, a glass top fitted within said ring, projections on said top remote from said ring and being adapted to engage said spring fingers when in one position of rotative adjustment within said ring, said spring fingers having means thereon to prevent removal of said top from said opening while permitting relative expansion between said top and lid and relative expansion between said spring fingers and top, and a second projection independent of said first projection for engaging the lid to thereby resist removal of said top from said lid while the top is in one position of rotative adjustment within said opening.

7. In a percolator, the combination with a lid having an opening therein, of a depending flange arranged about said opening, a glass top arranged within said opening and having a portion projecting below said flange, a sloping surface on said portion, sloping in a direction downwardly and outwardly away from said flange, a spring abutting against said lid and said sloping surface, and yieldingly urged in a direction toward the axis of said top for preventing removal of said top from said opening but permitting relative expansion of said top and said lid without destroying the operative engagement of said spring with said sloping surface, said sloping surface being arranged at a point remote from the adjacent portion of said flange, and an abutment thereon separate from said sloping surface to engage said lid for preventing removal of said top from said opening while the spring is in engagement with said sloping surface.

8. A glass percolator top comprising a member having a substantially cylindrical flange and two projections thereon substantially in alignment with each other in the direction of the axis of the cylindrical flange, each projection being adapted to co-operate with different retaining

means for holding said top within an opening in a percolator lid.

9. A glass percolator top comprising a member having a cylindrical flange adapted to fit in a circular opening in a percolator lid, a projection on said flange for preventing removal of said top from said opening by its engagement with the edge of said opening and arranged so as to lie in close proximity to said edge when said top is in said opening, and an abutment on said top adapted to lie at a substantial distance from the edge of said lid surrounding said opening when said top is in said opening, said last mentioned abutment being adapted to be engaged by resilient means on said lid to prevent rattling of said top in said opening regardless of whether said top fits snugly within said opening or not.
10. In a percolator cover, the combination with a lid having an opening therein, of a glass top having a cylindrical portion arranged within said opening, a projection on said top spaced a substantial distance from the portion of said lid adjacent said opening, a removable ring having a spring finger thereon, interposed between said projection and said lid with said spring finger engaging said projection and said ring engaging said lid, and a second projection on said top adapted to co-operate with the edge of said opening for preventing removal of said top from said opening, independently of said first projection and spring finger, while said top is in one position of rotative adjustment within said opening.
11. A percolator cover comprising a lid having an opening therein, of a ring having a portion for gripping the edge of said lid which surrounds said opening, a glass top having a flange arranged within said ring, a projection on said top remote from said lid, a second projection on said top adjacent said lid and adapted to co-operate therewith for preventing removal of said top from said opening, and a spring finger on said ring engaging said first projection.
12. In a percolator cover, the combination with a lid having an opening therein, of a glass top fitting within said opening, a projection on said top, a ring separate from said lid and top and arranged between said lid and projection, said ring having a rim portion adjacent said projection for engaging said projection and resiliently forcing said projection in a direction away from said lid so that said top is resiliently held in said opening.
13. In a percolator cover, the combination with a lid having an opening therein, of a glass top having a flange arranged within said opening with a portion of said flange below said lid, a projecting portion on said flange below said lid for preventing separation of said top from said opening when said top is in one position of rotative adjustment, said projecting portion having a depression therein surrounded by sloping walls, and resilient means arranged within said depression to engage said walls and abutting against the underside of said lid.
14. A percolator top comprising a body portion having a depending flange, and a projection on said flange substantially in the form of a one-half section of a right circular cone with the apex extending toward the main body of said top.
15. In a percolator cover, the combination with a lid having an opening therein, of a glass top having a flange arranged within said opening, a bead on said top for preventing the movement

of said top through said opening in one direction, a bayonet joint between said top and lid comprising a projection on said top and a recess in said lid, a second projection on said top, and a spring means for engaging said second projection and lid for preventing removal of said top from said lid, said spring means comprising a substantially rigid ring having a spring finger thereon adapted to engage said second projection and the underside of said lid, said ring being entirely free and separate from said top and lid and being held in operative relation with said top and lid only when said top is within said opening.

16. In a percolator cover, the combination with a lid having an opening therein, of a glass top having a depending flange, a projection on said flange, a ring having spring fingers thereon co-operating with the underside of said lid and with said projection for holding said top within said opening, said ring with said spring fingers being held in operative relation with said lid solely by the reaction between the same and said projection and lid, and being freely and bodily removable from said lid when said top is removed from said opening.

17. In a percolator top, the combination with a lid having an opening therein, of a substantially rigid ring engaging the underside of said lid, a top having a depending flange arranged within said opening, a plurality of projections spaced peripherally about said flange, and spring fingers carried by said ring for engaging said projections to hold said top within said opening and resist rotation of said top within said opening, said ring being wholly unconnected with said lid.

18. A device as claimed in claim 17 in which additional projections are provided spaced about the periphery of said flange for engaging the edge of said opening to prevent withdrawal of said top from said opening while said spring fingers are in engagement with said first mentioned projections.

19. In a percolator cover, the combination with a lid having an opening therein, of a glass top having a portion arranged within said opening, a bead for limiting the movement of said top into said opening, a bayonet slot in said lid at the edge of said opening, a projection on said top adapted to pass through said slot, and upon rotation of said top within said opening prevent the withdrawal of said top from said opening, a ring having a bayonet slot therein for the reception of said projection to enable said ring to be arranged about said top between said lid and said projection, said ring having spring means thereon for co-operation with said projection and lid when said ring is rotated after said projection has passed through said slot in said ring to thereby hold said top within said opening.

20. In a percolator cover, the combination with a glass top, of a lid having an opening therein, a depending flange on said top arranged within said opening, means on said top for limiting the movement of said top into said opening, a pair of projections on said flange spaced peripherally about said flange, a substantially continuous ring surrounding said flange and having an inwardly extending rim portion provided with a plurality of serrations so that as said ring is inserted over said flange and projections, and arranged between said projections and lid, the ring may be rotated to bring said projections into said serrations and prevent rotative movement of said ring relative to said flange in a peripheral direction.

and the removal of said top from said opening.

21. A glass top for percolators comprising a bead on said top for limiting the movement of said top into the opening provided in the lid of a percolator, and a flange adapted to be arranged within said opening, of a peripheral projection on said flange and spaced from said bead, and a conical projection having the apex thereof extending toward the spherical projection and substantially in alignment therewith in a direction parallel with the axis of said top.

22. A glass top for percolators comprising a body portion having a bead thereon, a depending flange, a pair of spherical projections spaced peripherally about said flange, and a pair of conical projections spaced peripherally about said flange with the axes of the conical surfaces extending in a direction toward said bead and the outer conical surfaces facing said bead.

23. A device as set forth in claim 21 in which the lower base portion of said conical projection has an outwardly extending shoulder at substantially right angles to the axis of said top.

24. A percolator top comprising a body portion having a bead thereon and a flange depending from said body portion and spaced inwardly from said bead, and a projection extending outwardly from said flange and provided with a recess therein for the reception of a holding means.

25. A glass percolator top having a substantially cylindrical apron arranged to fit into the opening of a percolator lid, a bead on said top to limit movement of said apron into said lid, said apron being provided with two spaced aligned projections one above the other.

26. A glass percolator top having a substantially cylindrical apron arranged to fit into the opening in a percolator lid, a bead on said top to limit the movement of said apron into said lid, said apron having a projection provided with an intermediate recess thus forming, in effect, two raised portions.

27. A glass percolator top having a substantially cylindrical apron arranged to fit into a percolator cover, a bead on said top to limit the movement of said apron into said lid, said apron being provided with two aligned projections one above the other, the lower projection being provided with a laterally extending retaining extension.

28. A glass percolator top having a substantially cylindrical apron arranged to fit into a percolator lid, a bead on said top for limiting the movement of said apron into said lid, said apron having a projection provided with an intermediate recess thus forming, in effect, two raised portions, the lower raised portion being provided with a laterally extending retaining extension.

29. A glass percolator top having a substantially cylindrical apron arranged to fit into a percolator lid, a bead on said top to limit the movement of said apron into said lid, said apron being provided with two aligned projections one above the other, the face of the lower projection being wedge shaped.

30. A glass top comprising a member having a cylindrical portion, limiting means adjacent said portion, a projection on said portion and located in spaced relation from said limiting means, and a second projection on said portion, having a wedge shaped face opposed to said limiting means.

31. A container lid having an opening therein, a glass top having a portion fitting into said open-

ing, means for limiting the movement of said top into said opening, a projection on said top portion spaced from said limiting means and adjacent said lid, a second projection of wedge shape on said portion with the face thereof opposed to said limiting means, and resilient means coacting with said face and said lid to hold said top connected to said lid.

32. A percolator top comprising a body portion having a limiting bead thereon, an apron depending from said body portion and spaced inwardly from said bead, and a projection extending outwardly from said apron and provided with a recess therein for the reception of a resilient holding means, and provided with a wedge-shaped portion the axis of which is parallel with the axis of the top and the apex of which is upwardly disposed in relation to the remainder of the wedge.

33. A container lid having an opening therein, a glass top having a portion fitting into said opening, means for limiting the movement of said top into said opening, a projection on said portion and spaced from said limiting means in position to engage the lid, a second projection on said portion, wedge shape, with the face thereof opposed to said limiting means, and resilient means having tongues thereon to contact said wedge shape projection for resisting rotation of said top and lid.

34. A container lid having an opening therein, a glass top having an apron portion fitting into said opening, means for limiting the movement of said portion into said opening, a projection on said portion and located away from said limiting means and adjacent said lid, a second wedge shape projection on said portion, and a spring means, said spring means shaped to extend above and past said first projection and yieldingly engage the wedge shape projection when said top is turned in said cover.

35. A container lid having an opening therein, a glass top having an apron portion fitting into said opening, means for limiting the movement of said portion into said opening, a projection on said portion located away from said limiting means and adjacent said lid, a second projection, wedge shape, on said portion, and an annular resilient ring, angle-shaped in cross-section, arranged to contact with the wedge shape projection to hold said top and lid together.

36. A ring, angle shaped in cross-section, having portions for contacting a percolator cover and also the face of a wedge shape projection on a percolator top for the lid of a percolator cover, said portion being a tongue for resiliently contacting the wedge shape projection, and one of said contacting portions also having serrations thereon.

37. A ring comprising a body portion of resilient material, resilient fingers extending therefrom and arranged to contact the lower of two vertically aligned projections on a percolator top.

38. A container lid having an opening therein, a glass top positioned in said opening, said top having a limiting bead, an apron extending downward from said limiting bead, and said apron having two spaced projections one above the other, and a ring with spring fingers contacting only the lower of said projections.

39. A container lid having an opening therein, a glass top, having a limiting bead thereon, positioned in said opening, an apron extending downward from said limiting bead having two spaced projections one above the other, and spring means

on said lid adapted to contact only the lower one of said projections.

40. A container lid having an opening therein, a glass top having an apron portion fitting into said opening, means for limiting the movement of said apron into said opening, two spaced projections on said apron one above the other in a direction away from the said limiting means, and a ring having spring fingers contacting only the lower one of said projections.

41. A container lid having an opening therein, a glass top having an apron portion fitting into said opening, means for limiting the movement of said apron into said opening, two spaced projections one above the other on said apron in a direction away from said limiting means, and spring fingers on said lid contacting only the lower one of said projections.

42. A cylindrical ring having an inturned resilient flange the edge of which is serrated.

43. A percolator top having a body portion, a raised limiting bead thereon, an apron extending from said limiting bead in a downward direction and being adapted to be arranged in an opening in a percolator cover, said apron having a projection provided with an intermediate recess thus forming, in effect, two raised portions.

44. A percolator top comprising a body portion, an apron extending from said body portion in a downward direction and being provided with two raised projections, the lower projection being provided with an extending retaining ex- 10 tension.
